[57] CLAIM

The ornamental design for a children's interactive scrolling calendar, as shown and described.

DESCRIPTION

FIG. 1 is a right side elevational view of a children's interactive scrolling calendar showing my new design; FIG. 2 is an end elevational view thereof, the undisclosed end being a mirror image;

FIG. 3 is a top plan view thereof, the broken lines shown are for illustrative purposes only and form no part of the claimed design;

FIG. 4 is a bottom plan view thereof;

FIG. 5 is a top perspective view thereof;

FIG. 6 is a bottom perspective view thereof; and,

FIG. 7 is a left side elevational view thereof.

The broken lines represent a roll of paper being used by the children to create the interactive calendar thereon.
